CLAIM

The ornamental design for a lips logo for bottle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a lips logo for bottle;

FIG. 2 is a front elevation view of the lips logo for bottle of FIG. 1;

FIG. 3 is a rear elevation view of the lips logo for bottle of FIG. 1;

FIG. 4 is a left side elevation view of the lips logo for bottle of FIG. 1;

FIG. 5 is a right side elevation view of the lips logo for bottle of FIG. 1;

FIG. 6 is a top plan view of the lips logo for bottle of FIG. 1; and,

FIG. 7 is a bottom plan view of the lips logo for bottle of FIG. 1.

The dash-dash broken lines shown in the drawings depict an environmental bottle that forms no part of the claimed design.

The dash-dot-dot broken lines define the bounds of the claimed design and form no part thereof.

1 Claim, 6 Drawing Sheets
